DESIGN FOR A DRESS

Henry Meisler, New York, N. Y.

Application May 8, 1939, Serial No. 84,858

Term of patent 3½ years

To all whom it may concern:

Be it known that I, Henry Meisler, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design;

Fig. 2 is the rear view of Fig. 1, and

Figure 3 is an enlarged fragmentary view of

the dress shown in Figure 1 illustrating one of the sleeve members as seen from the side.

The characteristic feature of my design resides in the combination on the dress disclosed of the specific embroidery extending down the front in association with the specific sleeve members as shown.

I claim:

The ornamental design for a dress, substantially as shown and described.

HENRY MEISLER.
